UNITED STATES PATENT OFFICE.

GEORGE RIEL AND WILLIAM RIEL, OF MANCHESTER, NEW HAMPSHIRE.

GUIDE FOR SOLE-SEWING MACHINES.

SPECIFICATION forming part of Letters Patent No. 747,225, dated December 15, 1903.

Application filed December 22, 1902. Serial No. 136,264. (No model.)

To all whom it may concern:

Be it known that we, GEORGE RIEL and WILLIAM RIEL, citizens of the United States, residing at Manchester, in the county of Hillsboro and State of New Hampshire, have invented certain new and useful Improvements in Guides for Sole-Sewing Machines; and we do hereby declare the following to be a full, clear, and exact description of the invention, such as will enable others skilled in the art to which it appertains to make and use the same.

This invention, which relates to guides for shoe-sole-sewing machines, is directed more particularly to improved means for adjusting the guide to effect variations in the line of stitching to accord with variations in the projecting portion of the sole.

The nature of the improvements will be readily comprehended, reference being had to the following detailed description and to the accompanying drawings, in which the invention is illustrated in its preferred form, it being understood that various modifications may be made therein without departing from the spirit of the invention as defined by the claims.

In the drawings, Figure 1 is a perspective view of a portion of a sole-sewing machine and a guide-adjusting means embodying the invention. Fig. 2 is a plan view, the positions of the parts being shown in full and dotted lines. Fig. 3 is a vertical sectional view on line 3-3 of Fig. 2.

Referring to the drawings by numerals, 1 denotes the post of a sole-sewing machine, and 2 is the throat-plate. The guide consists of a plate 3, adjustably supported on the throat-plate by screws 4, which occupy longitudinally-disposed slots 5 in the plate 3, the forward end 6 of the plate being formed to provide a proper guiding-surface and the rearward end 7 being downturned and provided with a threaded hole 8. A screw 9, having a thumb-head, is inserted in the hole 8 and bears at its inner end against the rear end of the throat-plate to limit the forward movement of the guide, such range of movement being, however, variable, accordingly as the screw 9 is adjusted. A jam-nut 10 serves to lock the screw 9 against accidental turning. At one side of the post is secured, by means

of a bolt 11, a plate 12, having at its rear end a laterally-bent portion 13 in a threaded hole in which is inserted a screw 14, forming the pivot of a lever 15. This lever extends transversely across the guide and engages a pin 16, projecting upwardly from the latter. Movement of the lever in the direction indicated by the arrow effects rearward movement of the guide through the engagement of the pin by the lever. Such rearward movement is against spring action, whereby upon the release of the lever the guide returns to its normal position. The bolt 11 extends through the post and its ends project sufficiently to engage with the hooked ends of coiled springs 17, which extend at the sides of the post and have opposite ends hooked into holes provided in side extensions 18 of the plate 3.

The lever is moved by the knee or by the foot of the operator, and to this end there is provided a lever 19, pivoted by a pin to a bracket 20, secured to the bench and having one arm 21 provided toward its extremity with a squared opening engaging the squared end 22 of the lever 15.

Movement of the levers 19 and 15 effects rearward movement of the guide from the normal position of the latter, which is predetermined by adjustment of the screw 9, and by reason of the multiplied leverage provided such movement of the parts is effected by a slight manual pressure and is therefore readily controlled.

The nature of the improvement enables its attachment to existing machines without modification, and the parts being few in number and simply constructed there is no liability to disorder.

We claim as our invention—

1. In a sole-sewing machine, the combination of a post, a throat-plate thereon, a guide-plate having a downturned rear end and mounted on the throat-plate to be moved longitudinally, a shoulder on the guide-plate, a pivoted lever in engagement with said shoulder, a knee or foot operated lever connected with the aforesaid lever, a set-screw at the downturned end for limiting the movement of the guide-plate, and a spring for retracting the guide-plate after movement.

2. In combination, a post, a throat-plate on the post, a plate at one side of the post, a

bolt securing the side plate and passed through the post, a guide-plate movable on the throat-plate, springs connecting the guide-plate with exposed ends of the bolt, a lever 5 pivoted at one end on the side plate, and a shoulder on the guide-plate in engagement with the lever.

In testimony whereof we affix our signatures in presence of two witnesses.

GEORGE RIEL.
WILLIAM RIEL.
